(57) **CLAIM**

The ornamental design for the rain blanket, as shown and described.

DESCRIPTION

A blanket with a self-contained carrying bag that can be converted into a sleeping bag with a pillow and a hooded raincoat.

FIG. 1. A top view of the rain blanket.

FIG. 2. A side view of the rain blanket.

FIG. 3 is an end view of the rain blanket;

FIG. 4 is an opposite end view of the rain blanket;

FIG. 5. A bottom view of the rain blanket

FIG. 6 is an opposite side view of the rain blanket;

FIG. 7. A perspective view of the rain blanket when used as a sleeping bag.

FIG. 8. A perspective view of the rain blanket when in the carry bag configuration; and,

FIG. 9. A side view of the rain blanket when in the hooded raincoat configuration.

The cross-hatched pattern shown in FIGS. 1,5,7,8 and 9 is understood to be repeated uniformly throughout the surfaces shown.

The broken line showing of the person is for illustrative purposes only and forms no part of the claimed design.
